UNITED STATES PATENT OFFICE.

JAMES A. WHITE, OF PHILADELPHIA, PENNSYLVANIA.

WINDOW-SCREEN.

No. 898,539.

Specification of Letters Patent. Patented Sept. 15, 1908.

Application filed December 12, 1906. Serial No. 347,418.

To all whom it may concern:

Be it known that I, JAMES A. WHITE, a citizen of the United States, and a resident of Philadelphia, in the county of Philadelphia and State of Pennsylvania, have invented certain new and useful Improvements in Window-Screens, which improvements are fully set forth in the following specification.

10 This invention relates to improvements in screens for window and similar openings; and more particularly to screens of that class commonly known, by reason of each thereof comprising relatively adjustable main 15 members, as adjustable window screens.

The object of this invention is to provide a window screen which may be cheaply constructed chiefly or wholly of metal, thereby materially enhancing its efficiency and durability; which shall be comparatively light in weight, simple in its details of construction, and convenient in its application to practical purposes; and which shall possess certain well-defined advantages over prior 25 analogous devices.

The invention consists in the novel combinations, parts and details of construction whereby, together with the novel disposition and relative arrangement of said parts, 30 the attainment of the foregoing object is rendered practicable, all of which will be hereinafter more specifically described and set forth in the appended claims.

The invention is clearly illustrated in the 35 accompanying drawings, wherein like reference-numerals denote corresponding parts throughout the several views, and as to the latter: Figure 1 is a face view of a window screen constructed in accordance with my 40 invention. Fig. 2 is a transverse section thereof, as along the line $x-x$ of Fig. 1. Fig. 3 is an edge view of same; and Fig. 4 is a detail cross-sectional view of one of the tie-rails made use of. Fig. 5 is a fragmentary 45 perspective view of one corner of the general frame structure showing the connection of the tie-rail made use of with the clamping ledge of the device.

In a general sense my present invention 50 comprises opposite side-rails connected by an end-rail, the said side-rails and end-rail being each formed from a single strip of metal; a clamping tie-rail, connecting said side-rails in opposition to said end-rail; and 55 a segment of open-mesh fabric, the latter secured marginally to said side-rails, re-

spectively, and said end-rail, and having its remaining margin clamped and held by said tie-rail.

It further comprises, in a general sense, a 60 pair of main members constructed, each, substantially as above specified, and means for holding said main members slidably together, whereby each may be adjusted relatively to the other. 65

In carrying out my invention, reference being had to the accompanying drawings, I provide opposing side-rails connected by an end-rail, each of which several rails is formed from a single strip of sheet-metal, folded 70 longitudinally, as at 2, and returned somewhat substantially upon itself, thereby forming a two-fold clamping ledge 3, one of whose constituent members is extended outwardly in the plane of said ledge to form 75 a rear side member 4, while the other is turned or bent forwardly substantially at right angles to said ledge to form an inner edge-wall 5; thence turned outwardly, parallel with the rear member 4, to form a front 80 side member 6; then turned backwardly to form an outer edge-wall 7; and then turned inwardly and terminated in a stiffening strip 8, at the forward face of the rear side member 4, the said ledge accordingly extending longitudinally along said rail at the inner side thereof, with its constituent members integrally connected along their inner edges, and each integrally connected along its outer edge with said rail proper, the latter 90 and said ledge being accordingly formed of one and the same material; and said side-rails and end-rails, respectively, being suitably mitered, and thereafter fastened together in any approved and well known manner, as by soldering at the points 9 and 10. 95

It will be observed that when the side-rails and end-rail are thus assembled, the ledge 3 extends continuously along one of said side-rails, the end-rail, and the opposite side-rail, 100 thereby materially strengthening the frame structure thus formed; and upon said ledge I dispose a segment or sheet of open-mesh fabric, 11, preferably constructed of wire, the same being primarily tacked or secured 105 thereto, at intervals therealong, by means of solder, or other appropriate holding medium. Thereafter I superimpose upon the fabric 11, along its margins co-inciding with the ledge 3, a fillet 12, securing the latter in place by 110 means of solder, or the like. The fillet 12 serves to more definitely insure the retention

of the fabric 11 in place upon the ledge 3; to strengthen the device as a whole, and as a finishing medium for the latter. The fillet 12 is formed, by preference, from a single strip of sheet-metal, bent longitudinally at intervals widthwise thereof, and so as to form a hollow completed structure of such cross-sectional contour as to adapt it to fit into and fill with fair nicety the rabbet of the side-rails and end-rail aforesaid, respectively, and substantially as illustrated in the drawings. The remaining margin of the fabric 11 is firmly held between the opposing clamping-members (Fig. 4) 13, 14, of the tie-rail 15, the latter connecting and firmly holding the ends of the respective side-rails and the twofold ledges thereof, opposite to the end-rail aforesaid, said tie-rail being soldered or otherwise firmly conjoined therewith.

The tie-rail 15 is primarily formed by longitudinally folding and returning a single strip of sheet-metal practically upon itself, thereby forming the opposing clamping-members 13, 14 thereof. Between these clamping-members is inserted the adjacent margin of the fabric 11; and thereafter said tie-rail as a whole is subjected to a suitable side-pressure, by means of an appropriate die, or other suitable device, whereby the clamping-members 13, 14, are simultaneously forced closely together and at the same time deflected sidewise in unison, thus causing them to firmly grasp and hold the margin of the fabric 11 inserted therebetween.

Ordinarily, I purpose to provide a pair of main screen members, each comprising parts formed, constructed and assembled substantially as herein described and illustrated in the drawings, the said main members being slidably conjoined in such a manner that each may be adjusted relatively to the other for the purpose of accommodating the adjustable device as a whole to openings of different widths. In this connection I purpose to make use of guide-clips, formed in any appropriate manner, and conjoined with the main screen members in such a manner that those carried by either of said main screen members will take partially around the side-rails, respectively, of the opposing screen member, substantially as shown in the drawings. Specifically, and as here shown, each of said guide-clips is formed from a piece of sheet-metal, of suitable rigidity, and comprises a main portion 16, whose inner end is grasped by, and held between, the opposing members of the ledge 3, from whence said main portion projects outwardly between the rear side-member 4 and the stiffening strip 8 of the rail in conjunction with which it is used; thence turned substantially at right angles rearwardly of said rail, and projected along the outer edge of the adjacent rail of the opposing main screen member; and then

returned substantially at right angles inwardly and terminating in a final portion 17, which projects inwardly along the front side-member 6, at the outer side thereof.

It will be understood that the number of guide-clips used in conjunction with each side-rail of the respective main screen members, and likewise the arrangement thereof with respect to such rail, may be varied as may be found desirable in practice. However, when arranged substantially as herein shown and described, those carried by one of the main screen members will collide with those carried by the other main screen member, under sufficient relative adjustment of the respective main screen members, and thus limit the adjustment of the latter in one direction, which is desirable. On the other hand, relative adjustment of said main screen members in the opposite direction may be freely continued until each is disengaged from the guide-clips of the other, and said main screen members may be taken apart or separated. By reversing this last named adjustment of the main screen members, the same may be reassembled for service as an adjustable window screen, as will also be readily understood.

It will be seen that my improved window screen is particularly well adapted for the purposes for which it is intended; and further that the same may be modified to a considerable extent, particularly as regards the means availed of for slidably holding the main screen members together, the general character of the open mesh fabric made use of, and various details of the general construction, without material departure from the spirit and principle of my invention.

Having thus described my invention what I claim and desire to secure by Letters-Patent, is:

1. A window screen comprising opposite metallic side-rails and a metallic end-rail connecting the same, each of said rails having at its inner side a two-fold ledge the constituent members of which are integrally connected along their inner edges, and integrally connected, each along its outer edge with said rail, said ledge extending along one of said side-rails, the end-rail aforesaid, and the opposite side-rail, upon said rails, respectively, being duly assembled; open mesh fabric disposed marginally upon and secured to the ledge aforesaid; and a metallic, clamping tie-rail, the latter connecting said side-rails oppositely to the end-rail aforesaid, and grasping and holding said fabric along its remaining margin, substantially as herein specified.

2. A window screen comprising opposite side-rails and an end-rail connecting the same, each of said rails being formed from a strip of sheet-metal, folded longitudinally and returned somewhat, thereby forming at

its inner side a two-fold ledge, the constituent members of which are integrally connected along their inner edges, and integrally connected, each along its outer edge with said rail, said ledge extending along one of said side-rails, the end-rail aforesaid, and the opposite side-rail, upon said rails, respectively, being duly assembled; open mesh fabric disposed marginally upon said ledge; a hollow, metallic fillet disposed upon and marginally along said fabric; and a metallic, clamping tie-rail, the latter connecting the two-fold ledges of the opposite side-rails of each of said main members, and grasping and holding the remaining margin of the fabric conjoined therewith; and clips, the latter conjoined with the side-rails, respectively, of each of said main members, and holding said members slidably together, substantially as herein specified.

3. An adjustable window screen comprising a pair of main members, each comprising opposite, metallic side-rails and a metallic end-rail connecting the same, and each of the respective rails of each of said members having at its inner side a two-fold ledge, the constituent members of which are integrally connected along their inner edges, and integrally connected, each along its outer edge with said rail, said ledge extending along one of said side-rails, the end-rail, and the opposite side-rail of each of said members, upon the several rails thereof being duly assembled; open mesh fabric disposed marginally upon and secured to the ledge aforesaid, of each of said members; metallic, clamping tie-rails, one connecting the two-fold ledges of the opposite side-rails of each of said main members, and grasping and holding the remaining margin of the fabric conjoined therewith; and means for holding said main members slidably together, substantially as herein specified.

4. An adjustable window screen comprising a pair of main members, each comprising opposite side-rails and an end-rail connecting the same, and each of the respective rails of each of said main members being formed from a strip of sheet-metal, folded longitudinally and returned somewhat, thereby forming a two-fold ledge at the inner side thereof, the constituent members of which ledge are integrally connected along their inner edges, and integrally connected, each along its outer edge with said rail, said ledge extending along one of said side-rails, the end-rail, and the opposite side-rail of each of said main members, upon the several rails thereof, respectively, being duly assembled; open mesh

fabric disposed marginally upon the ledge aforesaid of each of said main members; a hollow, metallic fillet disposed upon and marginally along the fabric conjoined with each of said main members; metallic, clamping tie-rails, one connecting the two-fold ledges of the opposite side-rails of each of said main members, and grasping and holding the remaining margin of the fabric conjoined therewith; and clips, the latter conjoined with the side-rails, respectively, of each of said main members, and holding said members slidably together, substantially as herein specified.

5. A rail for a window screen, formed from sheet-metal, folded longitudinally and returned somewhat to form a clamping ledge at the inner side thereof, thence turned forwardly, thence outwardly, thence rearwardly, and thence inwardly and terminated in a stiffening strip, and having a guide-clip clamped by said ledge, said guide-clip projecting outwardly therefrom, thence rearwardly thereof, and terminating in a final inwardly projecting member, substantially as herein specified.

6. A rail for a window screen, formed from sheet-metal, folded longitudinally and returned somewhat to form a ledge at the inner side thereof, thence turned forwardly, thence outwardly, thence rearwardly, and thence inwardly at an angle to the rearwardly projecting portion aforesaid, and terminating in a stiffening strip, substantially as herein specified.

7. A frame for a window screen comprising opposite side-rails and an end-rail connecting the same, each of said rails being formed from a strip of sheet-metal, folded longitudinally and returned somewhat, thereby forming at its inner side a twofold ledge, the constituent members of which are integrally connected along their inner edges, and integrally connected, each along its outer edge with said rail; and a clamping tie-rail, the latter formed from a strip of sheet-metal, folded longitudinally and thereby forming opposing clamping-members, said tie-rail connecting the twofold ledges of the opposite side-rails aforesaid, oppositely to said end-rail, substantially as herein specified.
